United States Patent Office

Des. 180,705
Patented July 23, 1957

180,705

HANDLE OR SIMILAR ARTICLE

Donald E. Stewart, Grand Rapids, Mich., assignor to Jervis Corporation, Grandville, Mich., a corporation of Michigan

Application March 5, 1956, Serial No. 40,457

Term of patent 14 years

(Cl. D10—8)

Fig. 1 is a perspective view from the top of a handle or similar article embodying my new design,

Figs. 2, 3, 4 and 5 are respectively top, front, rear and end views thereof, and

Fig. 6 is a cross section taken on the line 6—6 of Fig. 3 more emphatically to illustrate the novel design of the graspable portion of the handle.

I claim:

The ornamental design for a handle or similar article, substantially as shown.
